SALESMAN'S FOLDING SAMPLE CASE

Rudolph Arvid Silene, Los Angeles, Calif.

Application March 9, 1944, Serial No. 525,741

4 Claims. (Cl. 190—17)

1

My invention relates to salesman's folding sample case used by salesmen for displaying their goods for sale to customers. It is composed of a series of shelves on which samples of merchandise are carried.

An object of my invention is to provide a display basket having a series of shelves arranged one above the other and mounted to be shifted from the position of wall shelves to those of a series of terraced shelves, and provided with suitable mechanisms for making those adjustments and also provided with enclosure means which is hinged and latched on the sides of my basket in a manner to be quickly attached and detached for enclosure and display positions of my shelves.

I prefer to make my series of shelves progressively narrower from the bottom shelf upwardly to the minimum narrow width of the top shelf. By this arrangement of the shelves, when the positions of the shelves are arranged vertically one above the other, the basket is more conveniently carried about and in the same manner in which hand bags or suit cases and the like are carried, which is normally with one hand.

In combination with the adjustable features and forms mentioned above I provide complete means for covering the sides and top of my basket.

These enclosures are made in sections hinged and clasped together in manners which enable the salesman to quickly open the baskets for inspection purposes whereby a clear view may be had of the entire contents of the shelving.

Another feature of my invention which is not common with portable display baskets, is that its outside appearance is in a novel form and shape, not common or even known of competing baskets, whereby there is a novelty of appearance which does not indicate the contents within the basket as and when the salesman approaches a customer. Thus, there is a sense of curiosity on the part of the customer being approached to see what there is carried in my basket. Thus in many cases the mind of the customer is not already made up against the purchase of goods which they might observe from seeing the contents carried by the basket before the salesman had opportunity for making a display of all of the goods. The novelty of shape and arrangement of my basket when first presented to a given customer holds the customer's attention until the salesman has opportunity to present his goods for inspection. This is a highly desirable situ-

2

ation to be arrived at when a salesman first calls on a given customer.

Reference will be had to the accompanying drawings in which—

Fig. 1 is a perspective view of my basket opened up in display form with the side walls removed.

Fig. 2 is a perspective view of the basket when closed up in form to be carried about.

Fig. 3 is a transverse sectional elevation taken on the line 3—3 of Fig. 1, certain cover portions being obscured.

Fig. 4 is an end elevation of the open basket, as taken on the section line 4—4 of Fig. 1 with the nearer end member removed and parts broken away to clarify disclosure.

Fig. 5 is a perspective detail of the upper left hand corner of the top of the basket.

Fig. 6 is a detail portion of the lower left hand and rear corner of the basket showing a cut-out foot opening as it would appear looking toward the rear of Fig. 2.

Fig. 7 is a plan view of one of the shelves of my basket on the underside of which there is a locking means composed of a disk connected to locking rods by means of which the series of shelves are supported in fixed position in vertical arrangement in the basket frame.

Fig. 8 is a perspective detail of the locking means indicated in dotted lines in Fig. 7.

Fig. 9 is a perspective end view of the left end wall of the frame of my basket.

Fig. 10 is a section on line 10—10 of Fig. 9.

Fig. 11 is an enlarged detailed view of a locking catch, being a part of the mechanisms used in relation to the telescoping legs and being taken on the line 11—11 of Fig. 10.

Fig. 12 is a sectional detail taken along the line 12—12 in Fig. 9 showing parts of the linkage connecting the front and rear legs to effect simultaneous extension or retraction of the legs.

Fig. 13 is a view of what is shown in Fig. 12 but at right angles thereto.

The basket is made of any suitable material, either of wood, metal, sheet steel or aluminum or whatever material is found to be most desirable for forming any part of the device or basket.

The rigid part or framework of the basket is composed of the end wall members 2 which are provided with end flanges 3 to which there is fixed the rigid plates 4, see Figs. 3 and 4.

The basket here shown is provided with the bottom tray or shelf 5, middle tray or shelf 6 and the top tray or shelf 7. The middle tray or shelf 6 is secured to the end walls 2 by bolts 8 and this middle tray or shelf does not rock, but re-

mains in fixed position. The tray or shelf 5 is hinged by pins 9 to beam bars 10 and the other ends of the tray or shelf 5 is hinged by pins 11 to beam bars 12 and these bars 10 and 12 are hinged or supported on the bolts 8 at the end walls 13 of the tray or shelf 6. The upper ends of the beam bars 10 and 12 are hinged by pins 14 to rounded end blocks 15.

The blocks 15 are connected by a round bar 16 across the top tray or shelf 7 as is best shown in Fig. 1, the ends of which bar 16 are rigidly fixed into the blocks 15. The top tray or shelf 7 is hinged to the beam bars 10 and 12 by the hinge pins 17.

The tray or shelf 5 is the wider tray and carries a heavier load usually than the other trays or shelves and it is more apt to become contacted when loaded and moved about in service when the tray is in the inclined position as shown in Figs. 1, 3 and 4, but when the shelves are in vertically aligned position, as shown in the closed up form of Fig. 2, no danger then is occasioned by outside jarring contact with anything as relates to the tray or shelf 5 alone. Hence as a protective guard for the tray or shelf 5, when in positions as shown by Figs. 1, 3 and 4, there is provided the connecting link bars 18 shown as being made of angle iron, and the upper ends of these link bars 18 are hinged on the pins 14 to the block 15. The lower ends of the link bars 18 are provided with slots 19 through which pins 20 extend, said pins being mounted in and projecting from the end walls 21 of the tray or shelf 5. Thus, when the trays or shelves 5, 6 and 7 are moved from the inclined position, as shown in Figs. 1, 3 and 4, to the inclosed vertical position, the pins 20 slide up the slots 19 to inoperative position.

The rigid plate 4 is connected by a spring hinge 22 to the trap door 23 which is connected by a spring hinge 24 to the curved top cap 25 of the basket enclosure. This curved cap 25 is provided with a handle 26, see Fig. 2, by which the basket is carried about.

On the front side of the basket there is a removable cover composed of two pieces, the upper piece being indicated by 27 and the lower piece by 28. The piece 28 is mounted to be held in place by being slid down endwise in a slot or crack made by channel pieces 29 fixed alongside the walls 2, and is connected by hinges 30 to the upper piece 27. Snap latches 31 connect the piece 27 to the curved top cap 25. The bottom edge of the piece 28 is connected by snap latches 32 to a cross tie member 33 connected to the bottom ends of the front legs 34, see Fig. 1.

The rear legs are indicated by 35 and both sets of legs at their upper ends 37 and 38 are telescoped into sleeve members 38 and 39. The sleeve members 38 and 39 are circular in form and are longitudinally slotted along their confronting surfaces.

The upper ends 36 of the legs 34 have longitudinally extending slots 40 and communicating longitudinal cross slots 41. The slots 40 accommodate the upper ends of brace bars 43 which carry pivot pins 42 which slide in the slots 41. The lower ends of the bars 43 extend diagonally down to the lower ends of the legs 35 into longitudinally extending slots 44 wherein hinge pins 45 connect the brace bars 43 to the legs 35.

The bars 43, when the legs 34 and 35 are extended as is shown in Figs. 1, 3 and 4, act as tie rods to keep the front and rear legs from spreading apart.

When the legs are telescoped into the body of the basket, as is indicated by Figs. 2 and 9, the bars 43 serve to draw up the rear legs 35 as and when pressure is put upon the front legs only in the telescoping action of the legs within the body of the basket. On the other hand where the chief pressure in forcing the inward telescoping of the legs is applied to the legs 35, the bars 43 serve to push up the legs 34 after the hinge pins 42 slide to the upper ends of slots 41. When the telescoping action is completed whereby the legs are in a position indicated by Fig. 9, the legs are locked in that position by means of latch blocks 46, see Fig. 11.

These blocks 46 are supported in brackets 47 which extend from the top ends of the legs 35. Hinge pins 48 in the brackets 47 support the latch blocks 46. The blocks 46 have the upward catch projections 49 adapted to engage pins 50 fixed in the end walls 2 when the legs are telescoped into the basket as is indicated in Fig. 9. The blocks 46 have lower catch projections 51 adapted to engage fixed pins 52 projecting from end walls 2, see Fig. 4.

An arm 53 of the block 46 is connected by hinge pin 54 to a rod 55. A spring 56 is mounted over the rod 55 and is prevented from slipping upwardly on the rod 55 by the cotter pin 57. The rod 55 extends downwardly and its lower end 58 is hinged into a lever 59 fixed on the cross rod 60 which is hinged at each end to the rear legs 35.

A foot treadle 61 is mounted on the central portion of the cross rod 60 whereby a pressure on the treadle 61 by the foot, indicated by 62 in Fig. 3, causes the latch blocks 46 to become disengaged from the fixed pins 50 or 52. Screw eyes 63, see Figs. 4 and 9, are fixed into the rear legs 35 and abut the springs 56. When the treadle is released, springs 56 rock the block 46 to permit the catch projections 49 or 51 to re-engage the pins 50 or 52.

The mechanisms in relation to the telescoping of the legs 34 and 35 and the latch blocks 46 are mounted inside the end flanges 3 of the end walls 2 of the frame of the basket. These mechanisms are covered over by the end covers 64 fastened by any suitable means to the end walls 2 as is indicated by screws 65, see Fig. 2, thus making a complete enclosure of these latched mechanisms.

When the shelves or trays 5, 6 and 7 are mounted in the inclined positions as is indicated by Figs. 1, 3 and 4, they are locked in place by means of rods 66 which are hinged into a revolving disk 67, see Figs. 7 and 8, which disk is hinged at 68 at the underside of shelf or tray 7, see Figs. 3 and 7, whereby the ends of the rods 66 are made to extend outwardly and to contact the edges of the end walls 2. The movement of the disk 67 in its slight rotary movement is brought about by a pull and push rod 70 having a turned over handle end 71. This handle end is guided and is supported in position by a screw eye 72 in the bottom of the shelf or tray 7.

The trays or shelves as shown by Figs. 1, 3 and 4 are prevented from being rocked further toward a horizontal position by the small blocks 73, see Fig. 1, which are secured to the end walls 2 and which contact the underside of the connecting link bars 18.

Downward movement of the legs 34 and 35 is limited by blocks 74 which are fastened to the bottom edge of the walls 2 and which engage

pins 75 fastened into the legs 34 and slidable along the longitudinal slots in sleeves 39. Since the brace bars 43 connect the legs 34 to the legs 35 downward movement of the latter is also limited by the blocks 74.

When the trays or shelves assume vertical alignment positions as suggested by Fig. 2, the blocks 15 and round bar 16 assume a position corresponding to the curved top of the end walls 2. This position of the trays or shelves is retained by flat springs 76, fastened into grooves in the tops of the end walls 2 and projecting over the top of the blocks 15 and snapping into small notches 77, see Figs. 1 and 5.

The operation of raising the basket and lowering its legs whereby the basket stands on its own legs in an upward position is performed in the following way. The user will place his foot 62, see Figs. 3 and 6, on the foot treadle 61 and thereby will rock the treadle which pulls down the rod 55 and latch arm 53 to release the projections 49 of the blocks 46 from the pins 50, which then allows the body of the basket to be lifted while the legs are held to the floor, the basket moving upwardly until the blocks 74 contact the pins 75 and the projections 51 contact the pins 52. The pins 52 being fixed into the end walls 2 will thus hold the basket upwardly on its exposed legs.

To reverse the position whereby the legs are telescoped into the body of the basket, the foot treadle 61 is again pressed by the foot 62 which releases the projection 51 from the pin 52, and thereby allows the basket to be shoved downward over the legs until the projections 49 of the blocks 46 engage the fixed pins 50, see Figs. 9, 10 and 11, which puts the basket and legs in the relation indicated by Figs. 2 and 9.

As the legs 34 and 35 are set at an angle to each other, the feet of each set are nearer to each other when in the position as shown in Fig. 2, than when the legs are in position of Fig. 1. Thus if the telescoping action movement of the legs takes place while the feet of the legs are all on the floor, then a slipping movement of the feet takes place on the floor between the front and the rear legs.

The preferred method for this telescoping movement is for the operator to grasp the handle 26, see Fig. 2, and then press with his foot 62 on the treadle 61, see Figs. 3 and 6, and then rock the basket toward himself which then will raise the legs 34 free from the floor while the legs 35 remain on the floor, and in this position the complete telescoping, either upward or downward, may easily be performed as relates to the position of the legs in any situation.

When the operator understands this method it takes but a moment or two to make the desired shifting of the position of the legs.

I have used the terms "tray" and "shelf" in the alternative throughout the specification, but I intend the use of either term in its broadest sense to include all supporting means such as trays, shelves, holders, baskets, basins, etc. whereby articles, powders, liquids, etc., may be held in any suitable manner for security and/or display.

It is believed that the invention and many of its advantages will be understood from the foregoing description, and that numerous changes may be made in the form, construction and arrangement of the parts within the spirit and scope of the invention, the form hereinabove described being merely a preferred embodiment thereof.

I claim:

1. A display device comprising a frame, a series of display shelves, two parallel bars each pivotally mounted at about the same point in its length for substantially parallel movement on said frame, said parallel bars pivotally carrying one of said shelves on their upper, and another on their lower paired ends, a centrally disposed shelf immovably secured to said frame, the movement of said shelf supporting bars to display position oscillating said upper and lower shelves around and into offset positions relative to said fixed shelf, and the reverse movement of said bars carrying said movable shelves to a position within the confines of said frame with the shelves arranged one above the other, a supplementary brace bar pivotally connected at one extremity to the upper portion of a said parallel bar and at the other extremity to said lower shelf to help support a load of heavy material in said lower shelf.
2. A display device comprising a frame member, said frame member consisting of end plates and a back plate secured together, a shelf member positioned substantially centrally of said end plates and secured thereto to form with said end plates and said back plate a rigid structure, two parallel bars pivoted adjacent the ends of said fixed shelf member and inside of said end plates, a shelf member pivotally secured to the upper ends of said bars, and another shelf member pivotally secured to the lower ends of said parallel bars, the pivotal movement of said parallel bars carrying said upper and lower members around and into offset positions relative to said central fixed shelf, the reverse movement of said parallel bars carrying said movable shelf members to positions within the confines of said frame member with the said shelves one above the other, and a supplementary brace bar pivotally connected at one extremity to the upper portion of a said parallel bar and at the other extremity to said lower shelf member to add rigidity and support to the assembly.

3. A display device comprising a frame having end plates and a back plate secured together; a shelf positioned substantially centrally of said end plates and secured thereto to form with said end plates and said back plate a rigid frame structure; a supplementary back plate hinged to said back plate to encompass a portion of the back area of said frame member and the top thereof; a pair of parallel bars pivoted to each of said end plates, each pair lying between a said plate and an adjacent end of said fixed shelf; an upper shelf pivotally secured to upper portions of said parallel bars, and another shelf pivotally mounted on the lower ends of said parallel bars, the pivotal movement of said parallel bars oscillating said upper and lower shelf members in opposite directions around said central fixed shelf member and placing said shelf members in offset relation one to the other; means carried on one of said oscillating shelves for locking said shelf with said frame end in said offset relation, the reverse movement of said parallel bars carrying said movable shelf members to a position within the confines of said frame with said shelves positioned one above the other, and a supplementary brace bar pivotally connected at one extremity to the upper portion of a said bar and at the other extremity to said lower shelf member to help support a heavy load in said lower shelf.
4. A display device comprising a frame having side members; a pair of parallel links each pivot-

ally connected at a similar point in its length to a said side member; a series of superimposed shelves each wider than the one next above and each pivotally mounted in parallel arrangement on said links; an operating bar pivotally mounted to the upper free end portions of said links; complementary interlocking members on said bar and said frame, said mounting of frame, links, shelves and bar effecting a parallel arrangement whereby said shelves are movable to open parallel step arrangement or to closed parallel stacked relationship, at the end of which latter movement said shelves are automatically locked by said interlocking members; and a supplementary brace bar pivotally connected at one end to said operating bar and at its lower end to an outwardly extending portion of the lowermost of said shelves, at least one of said bar connections having also a sliding movement to take up lost motion, said brace bar supporting said lowermost

shelf and adding rigidity to the shelf assembly when in said open parallel step arrangement.
